UNITED STATES PATENT OFFICE

NORMAN V. CHRISTENSEN AND WALTER M. HANNEMAN, OF CHICAGO, ILLINOIS

SUPPORTING FRAME FOR SEWING MACHINES HAVING INTERCHANGEABLE SEWING HEADS

Application filed August 19, 1926. Serial No. 130,194.

The invention relates to new and useful improvements in a supporting frame for a sewing machine, and more particularly to the means for supporting the sewing head.

5 An object of the invention is to provide a supporting frame for sewing machines on which interchangeable heads may be mounted so that the same supporting frame may be used for building sewing machines having cooperating elements for a different character of sewing, as for example, a sewing machine for felling may be built on the same supporting frame as a sewing machine for flat seam work in connection with knit goods.

10 15 A further object of the invention is to provide a machine of the above type wherein the operating parts of the sewing machine are mounted on said supporting frame so that the work supporting arm is suspended in order to aid in the stitching of garments having tubular parts.

A further object of the invention is to provide a sewing machine of the above type wherein all the operating parts in the sewing head are actuated from a single eccentric member on the main shaft which is mounted in the supporting frame.

A still further object of the invention is to provide a supporting frame of the above type having a detachable sewing head in which are mounted trimming devices, a reciprocating needle bar, and cross thread laying devices, all of which are actuated by a single lever connection with an eccentric member on the main shaft.

These and other objects will in part be obvious and will in part be hereinafter more fully disclosed.

In the drawings which show by way of illustration one embodiment of the invention—

Figure 1 is a top plan view of a machine embodying the improvements;

Fig. 2 is an end view of the machine looking toward the end of the work supporting arm;

Fig. 3 is a vertical sectional view through the machine, and a portion of the supporting frame showing the manner of detachably securing the head to the supporting frame, the

head shown in said figure containing a needle bar as the only operated part;

Fig. 4 is a vertical sectional view through the frame showing a detachable needle head in side view, which needle head is equipped with a needle bar carrying a plurality of needles, a movable trimming blade, and cross thread laying devices;

Fig. 5 is an enlarged vertical sectional view at right angles to the main shaft, said section passing between the needle bar and the presser bar;

Fig. 6 is an enlarged detail showing the manner of detachably connecting the needle head with the main supporting frame;

Fig. 7 is a view partly in plan and partly in section of the parts shown in Fig. 5, with the top cover plate removed;

Fig. 8 is a view partly in section and partly in side elevation from the front of the machine, and

Fig. 9 is a perspective view of the supporting shaft for the lever which actuates the parts in the needle head as illustrated in Figures 5 to 8, inclusive.

The invention is directed to a sewing machine frame, and more particularly to a sewing machine frame in which is mounted a main operating shaft, which shaft is provided with an eccentric member adjacent one end thereof. The supporting frame consists of a base portion and an upwardly and laterally extending supporting member, near the upper end of which the main shaft is located.

Said supporting frame is provided with an integral projecting, substantially horizontal portion which is adapted to support the needle head. Mounted in this projecting portion is a lever which is connected by suitable means to the eccentric member on the main shaft, and thus the lever is oscillated. Detachably connected to this projecting member are interchangeable needle heads. These needle heads contain different associated operating elements, so that when one needle head is attached to the supporting frame, a machine may be built thereon for forming flat seams in knitted fabrics, and when another needle head is attached thereto, a machine may be built on said supporting frame

for forming two independent lines of stitching such as are used in felling or the like. In either case, the operating parts of the needle head are actuated by a single lever connection to the main operating shaft. The 5 supporting frame also has a depending member directly beneath the main operating shaft, at the opposite end of the shaft from the eccentric member which carries the work supporting arm, and this work supporting arm 10 terminates beneath the needle head. The work supporting arm carries a feeding mechanism and a complementary stitch forming mechanism, and of course, the work supporting arm will be supplied with the proper 15 operating elements to co-act with the selected needle head for building up the machine desired.

Referring more in detail to the drawings, 20 the invention consists in a supporting frame consisting of a base portion 1 having an upwardly and laterally extending part 2, which, as shown in the present embodiment of the invention, terminates at its upper outer end in a horizontally extending housing 3. The 25 main shaft 4 is journaled in this housing 3 and extends lengthwise thereof. It will be understood, of course, that from certain aspects of the invention, a different manner of supporting the main shaft may be provided 30 at the upper outer end of the supporting member 2. The main shaft 4 is provided with a crank 5 which is located near one end of the main shaft. At the end of the supporting 35 frame adjacent said eccentric member on the main shaft, there is a substantially horizontal, laterally projecting portion 6. This projecting portion is formed integral with the main supporting member 2, and may be cast therewith. Said laterally projecting member 40 6 is hollow and is provided with a cross bar or lug 7, at the top side thereof, and with a cross bar or lug 7' at the bottom side of said projecting member. Said bars or lugs are located at the outer end of said laterally 45 projecting portion (see Fig. 6). The laterally projecting portion 6 is also provided with supporting means 8 for a bushing 9 in which is mounted a shaft 10. This shaft 10 carries 50 a lever 11 which is preferably fixed thereto, and the lever 11 is connected by a link 12 with the crank 5 on the main shaft. When the main shaft rotates, the lever 11 will be oscillated, and the shaft 10 supporting the lever 55 will also oscillate on its supporting bearings.

Mounted on this laterally projecting portion are interchangeable needle heads. As shown in the drawings, one of these needle heads is provided with a reciprocating 60 needle bar only, while the other needle head is provided with not only a reciprocating needle bar, but with a movable trimming blade, and also movable cross thread laying fingers. In Fig. 3 of the drawings, the needle head which is indicated at 13, carries a needle 65

bar 14, and the needle bar 14 is reciprocated by the lever 11 through a link connection 15. This needle head is particularly constructed for building a sewing machine wherein the stitching mechanism is adapted for producing independent rows of stitching. In this case, it is only necessary to use a single needle or plurality of needles, so far as the needle head is concerned, and the necessary parts for controlling the needle threads. This is the 70 type of machine which has been built and illustrated in Figures 1 and 2. The needle bar 14 is shown as having two needles 16 and 17. The needle head is provided with a presser foot 18 mounted on a presser bar 19. This presser bar is moved downward by a suitable spring so as to hold the material against the work supporting arm 20 and the feeding device mounted therein. The work supporting 75 arm 20 for all types of machines built on the supporting frame, is carried by a depending member 21. The main operating shaft 4 extends across the upper end of the supporting frame 2, and the depending member 21 is directly beneath the end of the operating shaft 80 opposite the end carrying the eccentric member which operates the needle bar. Connections from the main operating shaft 4 extend down through said depending member 21 and thence along the work supporting arm 20. The machine built up by the use of this needle 85 head 13 is of the type shown in detail in the application of Norman V. Christensen, and Harold J. Le Vesconte, filed February 16, 1925, Serial No. 9,584, and no claim is made 90 herein to the particular construction of support for the work supporting arm and the operating mechanism therein.

The needle head 13 is provided with a cross bar or lug 22, cooperating with the cross bar, or lug 7, and also a cross bar or lug 23 for the cross bar or lug 7'. These lugs 22 and 23 are counter-bored so that suitable screws 24 may be used for securing the lug 22 to the lugs 7 and the lug 23 to the lugs 7'. Thus it is that the detachable needle head 13 is secured to the main supporting frame. The presser bar 19 is adapted to be raised by a rock lever 25 secured by a bracket 26 attached to the main supporting frame 2. This rock lever 25 is adapted to be operated by a treadle or knee shift and is connected by a link 27 to a rock lever 28 which is pivoted in the needle head. Said rock lever 28 is provided with a laterally projecting arm 29 which engages beneath a pin 30 carried by a collar 31 clamped to the presser bar 19. A suitable leaf spring 32 is provided for depressing the presser bar. The bracket 26 is one of the brackets which support the bar 33 on which 95 are mounted suitable tensions 34 for the stitching threads. The main operating shaft is rotated by a belt wheel 35 mounted on the end of the shaft adjacent the eccentric member or crank 5.

When it is desired to detach the needle head 13, all that is necessary is to disconnect the link 27 from the rock shaft to which it is connected, remove the spring 32 and disconnect the operating lever 11 from the link 15. The lever 11 remains as a part of the elements which are permanently mounted on the main supporting frame 2. An interchangeable head may be substituted for the head 13 for producing flat seams in knit material, and such a needle head is shown in Figs. 4 to 9, inclusive. Said needle head is indicated at 36. The needle head is provided with lugs 22 and 23 similar to the lugs on the needle head 13, and these lugs are secured to the main supporting frame by screws 24 as above described. The needle head 36 is provided with a needle bar 37 and this needle bar 37 is connected to the lever 11 of the main supporting frame by a link 15, similar to the link used in the needle head 13. The needle bar 37 is provided with three needles 38, 38, 38. Cooperating with the needles 38 are cross thread laying fingers 39 and 40. It is desirable to trim the edges of the fabric which are brought down into abutted or overlapped relation prior to the stitching of the edges together to form the flat seam. Such a type of seaming mechanism is very common in the art. It includes a stationary trimming blade mounted on the presser foot and a movable trimming blade cooperating therewith. The needle head 36 is provided with a movable trimming blade 41. The presser bar of the needle head 36 is indicated at 42. The presser foot is removed from the machine in the drawings for the sake of clearness. This presser bar 42 is depressed by means of a spring 43, and is raised by a rock lever 44 connected to the link 27 above described. This rock lever 44 extends beneath a pin 45 on a collar 46 fixed to the presser bar 42.

Mounted to oscillate on the presser bar is a sleeve 47. A bracket 48 carrying a movable trimming blade 41 is fixed to this sleeve. A bracket 49 is fixed to the outer end of the sleeve 47 and is provided with a ball stud 50 to which a link 51 is connected for oscillating the sleeve on the presser bar. This sleeve 47 has a limited movement on the presser bar and is pressed downwardly by means of a spring 52. The stationary member of the trimming mechanism is mounted on the presser foot, and the spring 52 will yieldingly press the movable blade 41 into engagement with the fixed blade on the foot. An arm 53 is secured to the presser bar 42, and this arm is forked so as to straddle a bearing on a vertical bar 54 which performs the double function of an oscillating shaft for actuating the trimming blade and the cross thread laying fingers, and also as a guide for the presser bar to prevent said presser bar from oscillating in its bearings. Said vertical shaft 54 carries a ball stud 55 and the link

51 is connected thereto. When the needle head 36 is selected in the building up of the machine, then a cross shaft 10 is selected constructed as shown in Fig. 9. This cross shaft 10 carries a disk 56 on the outer end thereof beyond the outer face of the laterally projecting portion 6 of the main supporting frame. This disk 56 carries a ball stud crank 57. A link 58 cooperates with said ball stud crank 57. The link 58 is connected at its other end to an arm 59 which is fixed to the vertical shaft 54. The arm 59 carries a ball on the end thereof which engages a suitable ball socket in the link 58. When the lever 11 is oscillated, it will oscillate the shaft 10, and the oscillations of the shaft 10 through the crank 57 will move the link 58 endwise back and forth, and thus oscillate the vertical shaft 54. A suitable cover plate 60 is provided for the detachable head 36 which houses the link 58. The cross thread laying devices are thread carrying devices and are provided with suitable eyes for the cross threads. The cross thread laying device 39 is mounted on a lever 61. The lever is fulcrumed on a bracket 62. This lever is oscillated by a link connection 63 with an arm 64 on the vertical shaft 54. The cross thread laying member 40 is fixed at its upper end to an arm 65 which is pivotally mounted in a bracket 66 supported by the needle head 36. A link 67 is connected to this arm 65 and oscillates the same on its support. Said link is pivotally connected to an arm 68 carried by the vertical shaft 54. The link 67 is pivoted on the same side of the axis of the arm 65 that the thread laying member 40 is secured to said arm, while the link 63 is pivoted to the lever 61 at the opposite side of the axis from that supporting the thread laying device 39. As a result, these thread laying devices 39 and 40 move toward and away from each other, and thus lay their threads across the center of the seam being formed. It will be noted from the above that the cross thread laying devices and the movable trimming device are all actuated from the vertical shaft 54, and the vertical shaft 54 is oscillated through the lever 11 from the same eccentric member which oscillates the needle bar. In other words, in order to mount a needle head of the type just described on a supporting frame for building up a machine which will do flat seaming in knit goods, it is only necessary to change the shaft 10 and the lever 11 will actuate all the operating parts in the needle head 36. Thus it is that the needle heads are interchangeable.

Of course, it will be understood that when the needle head is used for flat seam work, the feeding mechanism must be changed slightly and likewise the looper mechanism. The work supporting arm 20 is likewise capable of being disconnected from the supporting frame and another arm may be sub-

stituted therefor. This detachability of the work supporting arm forms no part of the present invention, but is shown, described and claimed in the application filed February 15, 1926, by Joseph Berger, Serial No. 88,298.

This needle head 36 used in connection with flat seam work, is provided with an arm 69 having thread guides for the needle threads. 10 This arm 69 is secured to a shaft 70 which is provided with a bracket 71 having a cam slot 72 therein. A pin 73 carried by a bar 74 fixed to a sleeve 75 on the presser bar 42 is adapted to oscillate the shaft and move the 15 arm 69 to different set positions, depending upon the thickness of the material beneath the presser foot.

From the above description, it will be apparent that there has been provided a supporting frame on which sewing heads may be interchangeably mounted for building up a machine for different characters of sewing. The supporting frame is precisely the same in both types of machine, therefore, 25 these supporting frames can be produced in large lots, machined and prepared for use, and when the demand is greater for one type of machine than for the other, a proper supply of supporting frames may be carried in 30 stock. Furthermore, if the demand exceeds the supply, a sewing machine of one character may be dismantled, that is, the sewing head removed therefrom, and the supporting frame used for building the type of machine demanded. Furthermore, it will be 35 noted that in the type of supporting frame just described, there are comparatively few angular parts, as the sewing head is separate from the supporting frame. This greatly aids in the casting of the parts.

While there have been shown overlapping sections or lugs for securing the detachable head to the main supporting frame, it will be understood, of course, that the particular 45 manner of connecting the head to the supporting frame may be greatly modified. In fact, connecting dowel pins may be used and laterally projecting ears formed on the parts to be united, through which suitable screws 50 may be passed for joining the sections together.

It is obvious that other changes in the details of construction may be made without departing from the spirit of the invention 55 as set forth in the appended claims.

Having thus described the invention, what we claim as new and desire to secure by Letters-Patent, is—

1. A sewing machine including in combination, a supporting frame, a main shaft mounted on the upper portion thereof and having an eccentric member adjacent one end, said frame having a substantially horizontal laterally projecting portion at the end of the main shaft having the eccentric member, and

means for interchangeably connecting sewing heads to said projecting portion and the operating parts in said heads to said eccentric member, said interchangeable heads having operating parts for cooperating in making different seams whereby sewing machines may be built on the same supporting frame for producing different sewed articles. 70

2. A sewing machine including in combination, a supporting frame having a housing at the upper portion thereof, a main shaft journaled in said housing and extending lengthwise thereof, and having an eccentric member at one end thereof, said housing having a laterally projecting portion at the end of the main shaft having the eccentric member, and means for interchangeably connecting sewing heads to said projecting portion and the operating parts in said sewing heads to said eccentric member, said interchangeable heads having operating parts for cooperating in making different seams, whereby sewing machines may be built on the same supporting frame for producing different sewed articles. 75 80 85

3. A sewing machine including in combination, a supporting frame, a main shaft mounted in the upper portion thereof and having an eccentric member at one end thereof, said frame having a laterally projecting portion at the end of the main shaft having the eccentric member and having a depending portion at the other end of said shaft on which a work supporting arm is suspended, and means for interchangeably connecting sewing heads to said projecting portion of the frame and the operating parts in said sewing heads to said eccentric member, said interchangeable heads having operating parts for cooperating in making different seams whereby sewing machines may be built on the same supporting frame for producing different sewed articles. 90 95 100 105

4. A sewing machine including in combination, a supporting frame, a main shaft mounted in the upper portion thereof and having an eccentric member adjacent one end, said frame having a substantially horizontal laterally projecting portion at the end of the main shaft having the eccentric member, said laterally projecting portion extending substantially at right angles to the main shaft, and means for detachably connecting a sewing head to said projecting portion and the operating parts in said head to said eccentric member. 110 115 120

5. A sewing machine including in combination, a supporting frame, a main shaft mounted on the upper portion thereof and having an eccentric member at one end, said frame having a substantially horizontal laterally projecting portion at the end of the main shaft having the eccentric member, a lever mechanism journaled in said projecting portion and connected to said eccentric member, 125 130

means for detachably connecting a sewing head to said projecting portion and the operating parts therein to said lever mechanism.

6. A sewing machine including in combination, a supporting frame having a horizontal housing at the upper edge thereof, said frame being curved so that said housing overhangs the frame, a main shaft journaled in said housing, said frame having a laterally projecting hollow portion at one end of said main shaft, and a depending portion at the other end of said main shaft, said depending portion carrying a work supporting arm which is suspended and spaced from said supporting frame, a lever mechanism in said laterally projecting portion on said frame, and means for detachably connecting a sewing head to said laterally projecting portion and for connecting the operating parts in said sewing head to said lever mechanism.

7. A sewing machine including in combination a supporting frame, a main shaft mounted on the upper portion thereof and having an eccentric member adjacent one end, means for interchangeably connecting sewing heads to said frame at one side of the main shaft and the operating parts in said heads to said eccentric member, said interchangeable heads having operating parts for cooperating in making different seams whereby sewing machines may be built on the same supporting frame for producing different sewed articles.

In testimony whereof, we affix our signatures.
